EMERGENCY CUTTING TOOL FOR RESCUE OR THE LIKE

Clarence W. Daniels, P.O. Box 837,
Vacaville, Calif. 95688

Filed Feb. 10, 1969, Ser. No. 15,710

Term of patent 14 years

Int. Cl. D8—02

U.S. Cl. D8—89

FIG. 1

FIG. 2

FIG. 3

FIG. 4

FIG. 5

FIGURE 1 is a side elevational view of an emergency cutting tool for rescue or the like, showing my new design, the opposite side being substantially similar in appearance;

FIGURE 2 is a top plan view;

FIGURE 3 is a bottom plan view;

FIGURE 4 is a front end view; and,

FIGURE 5 is a rear end view.

I claim:

The ornamental design for an emergency cutting tool for rescue or the like, as shown and described.
